UNITED STATES PATENT OFFICE.

FRANK W. SMITH, OF WESTFIELD, NEW JERSEY.

TIMING DEVICE.

1,301,613.

Specification of Letters Patent. Patented Apr. 22, 1919.

Application filed March 2, 1916. Serial No. 81,623.

To all whom it may concern:

Be it known that I, FRANK W. SMITH, a citizen of the United States, residing at Westfield, in the county of Union and State 5 of New Jersey, have invented certain new and useful Improvements in Timing Devices, of which the following is a specification.

My present invention relates to a timing 10 device by which to so control the operation of a motive force as to introduce a determinable time interval between the application of such force and the production either in whole or in part of its operative effect.

15 The object of the invention is to provide a timing device, more particularly for a magnetic circuit or electromagnet although also applicable to other and purely mechanical fields, which is simple in construction, 20 readily adjustable, efficient, and durable and is not liable to get out of order and consequently requires little attention.

With this object in view my improved 25 timing device comprises as its principal distinguishing feature a member which is inclosed and sealed within a casing or container, as required, within which it is free to move from one to another position at a determinable rate or time interval and 30 thereby to secure the desired timing effect.

In the various forms in which the device is 35 capable of practical application, the timed movement of this member within its container may be effected in any suitable manner, electromagnetically or by gravity for example, and may perform its function either by changing the condition of a magnetic circuit or mechanically. The invention also includes the novel features of construction, arrangement, and combination of 40 parts hereinafter fully described and pointed out in the appended claims.

The invention will be understood by reference to the accompanying drawings, illustrating several different modes of application and appropriate forms of the timing device, in which—

Figure 1 is a view, partly in section and partly in elevation, of a long-pull electro- 50 magnet of the solenoid type equipped with my new timing device; Fig. 2, a like view showing a modification of the timing device as applied to the control of a solenoid; Fig.

3, a like view showing a timing device of somewhat different form inserted in and 55 forming a part of the armature of another common type of electromagnet; Fig. 4, a plan view from below, partly broken away, of the armature shown in Fig. 3; Fig. 5, a view, also in section and elevation, showing 60 a modification of the timing device as applied to a solenoid and rendered operative thereby to control the operation of an electromagnetically-actuated switch; and Figs. 6 and 7, like views showing a timing device 65 similar to that illustrated in Fig. 5 rendered operative by the actuation of a solenoid to mechanically control the operation of a switch, the various movable parts being shown in different positions in the two figures. 70

Referring first to Fig. 1, in which is illustrated what is perhaps the simplest application of my invention, a solenoid, consisting of a helix or coil 1 wound upon the usual spool and mounted within a magnetic frame 2 is provided with a plunger specially constructed so as to delay the action of the solenoid when energized and serve as a timing device therefor. The plunger comprises a cylindrical outer casing or container 3, of suitable non-magnetizable material, which is closed by a cap 4 screwed into its threaded upper end or otherwise suitably secured thereto, and, within the sealed chamber thus formed, the usual soft iron or other magnetizable core 5, normally resting by gravity upon an adjusting screw 6 set into the bottom of the casing and of such diameter as to leave a narrow annular passage between 90 its surface and the inner surface of the casing, and a suitable fluid, glycerin or an oil for example, which completely fills the space within the chamber not occupied by the core. To the cap forming the upper end of the 95 plunger is secured a pin or stem 7 which passes through a central opening provided therefor in the top of the solenoid frame and carries on its threaded upper end a nut 8 by which the plunger is normally supported on the frame at the limit of its downward movement and by which such position may be regulated.

In this form of the device, the air-gap left in the magnetic circuit by the magnetic core 100 in position at the bottom of its stroke restricts

the magnetic flow, when the circuit through the solenoid winding is closed, and the coil is energized, to a value insufficient to overcome the weight of and so raise the plunger as a whole but sufficient to raise the core within the casing, slowly because the fluid thereby displaced must work through the annular passage described from the upper to the lower end of the chamber. As the core rises, however, the air-gap at its top is gradually reduced and the magnetic flow over the circuit increases until it reaches a value sufficient to overcome the weight of the entire plunger, whereupon the plunger is raised bodily, practically instantaneously, after it starts to move, and the pin or stem carried at its upper end, by tripping a latch or actuating an electric switch for example, does the work for which the solenoid is employed.

The operation of the solenoid and the period of delay introduced by the timing device may easily be regulated as desired, either by means of the adjusting screw 6 or nut 8 or both. Thus, the critical value of the solenoid, that is to say, the value of the magnetic flow required to raise the outer casing of the plunger to instantly perform the work required of the solenoid, is determined by properly adjusting the position of the casing within the coil by means of the nut; and, this having been done, the time taken by the solenoid to reach its critical value, longer or shorter as desired, is obtained by lowering or raising the adjusting screw to change the position of the magnetic core within the casing.

As modified in Fig. 2, the spool upon which is wound the coil 11 of the solenoid is mounted between two iron heads 12 and 13. The plunger, which as before comprises a soft iron core 14 inclosed and sealed within a casing 15 filled with fluid, is supported at the limit of its downward movement by an arm 16 carried by a stem 17 depending from one side of the lower solenoid head. Surrounding the casing 15 is a helical spring 18 which at its lower end bears against a shoulder 19 formed around the casing and at its upper end against an annular ring 20 adjustably secured upon the stem 17 by means of a set screw 21. An arm 22, of iron or other magnetizable metal, is pivoted at its lower end to a lug 23 carried by the lower solenoid head and its upper end is adjustably secured in position, by a set screw 24, upon a curved segmental arm 25 projecting outwardly from the upper solenoid head. A rod or stem 26, mounted to reciprocate within a central opening in the upper solenoid head and supported normally therein by a collar 27, carries yieldingly or otherwise suitably mounted upon its upper end the movable contact member 28 of an electric switch.

The operation of the plunger as a timer

device is here substantially the same as in the device shown in Fig. 1, but the means of adjustment provided for its regulation are different. The position of the magnetic core at the bottom of its stroke, and consequently the length of the air-gap at its upper end, is fixed, but by changing the position of the arm 22 to lengthen or shorten the second air-gap in the magnetic circuit, between its upper end and the upper solenoid head, the value of the magnetic flow and its effect upon the magnetic core may be suitably regulated; and, in addition, by varying the tension of the spring 18 by shifting the position of the annular ring 20, what may be called the effective weight of the plunger may be increased or diminished to correspondingly increase or diminish the time interval required by the upward movement of the magnetic core to close the air-gap above and build up the magnetic flow to a value sufficient to raise the outer casing of the plunger and thereby actuate the movable contact member to close the switch above.

As illustrated in Figs. 3 and 4, the timing device is inserted in and forms a part of the armature of an electromagnet, which, as is common, consists of a coil 31 wound as usual upon a spool and mounted upon a magnetic iron core 32 between heads 33 and 34 secured to its ends. The armature of the magnet, which as shown is pivoted at one end to the magnet head 33 and at its other end carries a contact and constitutes the movable contact member of an electric switch, comprises two magnetizable metal pieces 35 and 36 separated by a rectangular casing or container 37, of suitable material to provide an air-gap in the member, to the flanged upper sides of which the adjacent ends of the two pieces are secured. A loosely fitting flanged plate or piston 38 of magnetizable metal is mounted within the casing, which is filled with a suitable fluid and sealed by a cap 39, preferably of non-magnetic material, secured to its upper end. The outer free end of the armature is adjustably held in normal open position by means of an arm 40, depending from the magnet head 34, in the lower flanged end of which is set an adjusting screw 41 bearing against the lower side of the armature.

When the coil of this magnet is energized the magnetic flow over the magnetic circuit, which includes the air-gap normally provided in the armature by the casing of the timing device and a second air-gap between the outer end of the armature and the adjacent magnet head, serves at first only to slowly raise the magnetic piston within the sealed chamber of the casing, against the retarding action of the fluid therein, and thereby to gradually close the air-gap in the armature and secure an increased magnetic

flow which, after a determinable time interval, reaches the critical value required to raise the armature and close the switch. It is obvious that the critical value of the magnet, and consequently the period of the delay in its action, may be regulated by turning the adjusting screw 41 up or down to vary the normal open position of the armature; also that, when the armature once begins to move, the value of the magnetic flow increases rapidly and the switch is closed instantly.

In still another application of the invention, shown in Fig. 5, the timing device is interposed between the plunger 61 of a solenoid 62, both of usual or any suitable construction, and an electromagnet which comprises the usual coil 63, a fixed magnetic core with two parallel legs 64 and 65 located one within and the other outside the coil, and the usual armature 66, pivoted to the lower end of the outer leg of the core and adjustably held in suitable position below the inner leg. The timing device here consists of a container 67 which is pivotally mounted at 68 and at its inner (left hand) end is connected by a link 69 to the lower end of the solenoid plunger and at its outer (right hand) end extends out over the upper ends of the core of the magnet. Mounted to slide within the container, which is filled with a fluid and sealed by a cap, is an elongated piston 70 of magnetizable metal, having a central longitudinal passage 71 controlled by a valve 72 so arranged as to permit the fluid confined within the container to pass freely through the passage as the piston moves from right to left therein but to retard its movement in the opposite direction.

Thus, when the solenoid winding is de-energized and its plunger drops by gravity, the pivoted container is tilted up to what may be called its normal position, shown in full lines in the figure, the piston sliding quickly down to and resting against the lower inner end of the chamber of the container. When, on the other hand, the solenoid is energized and raises the plunger, the container is tilted downwardly so as to bring its outer end into close proximity to the upper ends of the magnet core, as shown in dotted lines, whereupon the heavy magnetic piston, sliding by gravity slowly down to the outer end of the chamber, gradually closes the gap between and magnetically bridges the upper ends of the magnet core until the value of the magnetic flow over the circuit thus completed becomes sufficient to raise the armature of the electromagnet. When the solenoid winding is again de-energized and the outer end of the container is raised, the circuit of the electromagnet is broken and its armature drops. By adjusting the normal open position of the ar-

mature to change the critical value of the electromagnet the period of the delay in its action can to a certain extent be regulated.

In the last modification shown, Figs. 6 and 7, the construction of the timing device is substantially the same as in the last preceding figure. In this case, however, the piston 73 with valve-controlled passage mounted within the fluid filled container 74 need not be magnetizable since it performs its function in a purely mechanical manner. The inner end of the container is operatively connected by the perforated lug 75 with a stem 76 extending downwardly from the plunger of a solenoid, the two nuts 77 by which the lug is secured to the stem allowing it a certain amount of movement thereon.

Normally, the solenoid being deenergized, the container is tilted up and the piston therein rests against the lower inner end of the closed chamber, as shown in Fig. 6. When the solenoid is energized and draws up its plunger, the container is at once tilted downwardly to the position shown in full lines in Fig. 7, where it is stopped and held by a stem attached to the piston of the dash-pot 78 until the slowly descending piston passes the pivotal support of the container and further tilts it, against the action of the dash-pot, to the position shown in dotted lines in Fig. 7. By such further movement the outer end of the container is pressed down upon and closes the movable contact member 79 of a switch normally held in open position by a spring.

In case the fluid with which the container of the timing device is filled is a liquid, it will be understood that it is desirable to make some suitable provision for differences in the rate of expansion of the several parts under changes in temperature. This may be done, for example, by leaving a small quantity of air within the container or by inserting therein a piece of compressible material such as cork, in the form of a disk 80, secured in one end of the container (see Fig. 1) or to an end of the movable member.

One of the chief advantages of my improved timing device is that both the movable member or element and the fluid by which its movement is timed are sealed within a closed container so that its working parts are completely protected from dust, dirt, and corrosion. Again, since the movable member is not physically connected with any part outside the container, there is no stuffing box or other packing to wear out and permit leakage of the timing fluid. So far as the condition of the timing fluid may be affected by changes in temperature, the changes are always in the right direction. And, furthermore, the timing device is adapted for use under widely varying conditions because of its ready adjustability and

by reason of the fact that its movable element may be actuated either electromagnetically or by gravity and may perform its function either by changing the condition 5 of a magnetic circuit or mechanically.

While I have explained the principle of my invention and have fully described what I now consider to be the best modes in which to apply that principle in several of its different applications, it will of course be 10 understood that the invention may be further modified in its details and applied in still different ways without departing from the principle or sacrificing the advantages 15 thereof.

What I claim as new, and desire to secure by Letters Patent, is—

1. A timing device comprising a stationary electromagnet, a movable element, and 20 interposed between the two a movably mounted casing containing a body of fluid and a member adapted to move from one position to another therein at a rate determined by the rate of displacement of the 25 fluid, the several parts being so operatively combined that on the energization of the electromagnet the movable element will be actuated but only after the time interval required for the member within the casing 30 to move from one position to another therein.

2. A timing device comprising a stationary electromagnet, an electric switch, a movably mounted sealed casing containing a body of fluid, and a member located within 35 the casing and adapted to move from one position therein to another at a rate determined by the rate of displacement of the fluid, the several parts being so operatively combined that the electromagnet on being 40 energized will effect a movement of the casing and thereby the actuation of the switch but only after the time interval required for the member within the casing to move therein from one predetermined position to another. 45

3. A timing device comprising a movable element, an electromagnet for actuating the movable element, a sealed casing containing a body of fluid mounted to move within the 50 magnetic field, and a magnetizable core mounted within the casing and adapted to move therein at a rate determined by the rate of displacement of the fluid, the several parts being so operatively combined that the 55 electromagnet becomes effective to actuate the movable element only when the casing and the core therein occupy determinable positions within the magnetic field.

4. A timing device comprising a movable 60 element, an electromagnet, a sealed casing containing a body of fluid mounted to move within the magnetic field and adapted by its movement to actuate the movable element, and a magnetizable core located within the 65 casing and adapted to move therein at a rate

determined by the rate of displacement of the fluid, the several parts being so operatively combined and adjusted that the electromagnet when energized will effect a movement of the core within the casing and, after 70 the core reaches a determinable position therein, will effect a movement of the casing to actuate the movable element.

5. A timing device comprising a magnetic circuit, a casing of non-magnetizable material containing a body of fluid mounted to move within the circuit, and a magnetizable core located within the casing and adapted to be moved therein by the magnetic flux in the circuit at a rate determined by the 80 rate of displacement of the fluid, the parts being normally so supported, the casing with respect to the circuit and the core within the casing, that the magnetic flux in the circuit will be insufficient to move the casing until the core has been moved a predetermined distance therein.

6. A timing device comprising a magnetic circuit, a sealed casing of non-magnetizable material containing a body of fluid 90 mounted to move within the circuit, a magnetizable core located within the casing and adapted to be moved therein by the magnetic flux in the circuit at a rate determinable by the rate of displacement of the fluid, and 95 means for adjusting the operative relationship of the parts so that the casing will not be moved until the core has been moved therein a predetermined distance.

7. A timing device comprising a magnetic 100 circuit, a sealed casing of non-magnetizable material containing a body of fluid mounted to move within the circuit, a magnetizable core located within the casing and adapted to be moved therein by the magnetic flux in 105 the circuit at a rate determinable by the rate of displacement of the fluid, the casing being normally so supported with relation to the circuit that the magnetic flux will be insufficient to move the casing until the core has 110 been moved therein a predetermined distance, and means for regulating the value of the magnetic flux required to start the movement both of the core and of the casing.

8. The combination, in a solenoid, of a 115 magnet coil and a compound plunger which comprises a casing of non-magnetizable material containing a body of fluid and a magnetizable core adapted to move therein at a rate determined by the rate of displacement 120 of the fluid and which is so supported within the coil that the magnetic flux will be insufficient to raise the plunger as a whole until the core has been raised a predetermined distance within the casing.

9. The combination, in a solenoid, of a 125 magnet coil, a compound plunger which comprises a casing of non-magnetizable material containing a body of fluid and a magnetizable core adapted to move therein at a 130

- rate determined by the rate of displacement of the fluid and which is normally supported with relation to the coil so that the magnetic flux is insufficient to raise the plunger as a whole until the core has been raised a predetermined distance therein, and means for regulating the value of the magnetic flux required to start the movement of the core within the casing.
10. The combination, in a solenoid, of a magnet coil, a compound plunger which comprises a casing of non-magnetizable material containing a body of fluid and a magnetizable core adapted to move therein at a rate determined by the rate of displacement of the fluid and which is normally supported with relation to the coil so that the magnetic flux is insufficient to raise the plunger as a whole until the core has been raised a predetermined distance therein, and means
- 15 for regulating both the value of the magnetic flux required to start the movement of the container and the time required to obtain such value.
11. The combination, in a solenoid, of a magnet coil, a compound plunger which comprises a casing of non-magnetizable material containing a body of fluid and a magnetizable core adapted to move therein at a rate determined by the rate of displacement 30 of the fluid and which is normally supported with relation to the coil so that the magnetic flux is insufficient to raise the plunger as a whole until the core has been raised a predetermined distance therein, and means 35 for adjusting the normal position both of the casing within the magnetic coil and of the core within the casing.
